(57) **CLAIM**

The ornamental design for an enclosure for a mousetrap, as shown and described.

DESCRIPTION

FIG. 1 is a top perspective view of an enclosure for a mousetrap according to the present design;

FIG. 2 is a top plan view thereof;

FIG. 3 is a bottom plan view thereof;

FIG. 4 is a front elevation view thereof;

FIG. 5 is a rear elevation view thereof;

FIG. 6 is a left side view thereof;

FIG. 7 is a right side view thereof;

FIG. 8 is a top perspective view thereof;

FIG. 9 is a top perspective view, showing the lid in an open configuration;

FIG. 10 is an enlarged view of the encircled portion in FIG. 9;

FIG. 11 is a bottom perspective view, showing the lid in a partially open configuration;

FIG. 12 is an enlarged view of the encircled portion in FIG. 11;

FIG. 13 is a top perspective view, showing the lid in an open configuration; and,

FIG. 14 is an enlarged view of the encircled portion in FIG. 13.

The broken lines depict environmental structure and are included for the purpose of illustration only and form no part of the claimed design.
